GUN WITH REMOVABLE LINER

Filed Dec. 17, 1928

UNITED STATES PATENT OFFICE

GORDON M. WELLS, OF SAN DIEGO, CALIFORNIA, AND GEORGE M. McCANN, OF NEW CASTLE, DELAWARE

GUN WITH REMOVABLE LINER

Application filed December 17, 1928. Serial No. 326,687.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to us of any royalty thereon.

5 The subject of this invention is a gun with removable liner.

In the most successful type of gun with removable liner, an initial clearance or play space exists between the liner and the surrounding tube but its amount is very small. 10 The liner is thin and when subjected to pressure on firing it dilates into contact with the tube and then both elements expand together. The tube confines the liner within its elastic limit and by preventing deformation, insures the reestablishment of the initial clearance. 15 In those guns which were actually constructed in accordance with the formula, including the principle of initial clearance when using a very thin liner, it was essential that the dimensions of the liner and tube be exactly followed. An adherence to such precise requirements would not only preclude quantity production but due to the effect of 20 repeated firing on the tube, it would require that a new liner to replace the worn one which is removed be calibrated to conform to the worn tube. This condition defeats the very purpose for which the loose liner is 25 designed.

In seeking a method whereby all liners may be interchangeable with respect to all tubes of a given caliber we have discovered that under certain conditions adherence to 30 the precise dimensions developed from the gun formula is unnecessary and that such a manufacturing tolerance may be permitted in the fabrication of the liner and the tube as will insure interchangeability.

35 A determination of the most favorable tolerance must be based on a consideration of the function of an outer tube in a composite barrel and the role that it plays in reducing the total weight of the barrel to a 40 minimum. Obviously, in a single barrel

having a thickness calculated to include a safety factor to make it self-sustaining, there is a recovery to normal internal dimensions after firing. Considering such a barrel as a liner, the outer tube could be of negligible strength in so far as restraint of the liner against radial expansion is concerned but, inasmuch as the outer tube must serve to oppose or resist the longitudinal strains transmitted to it by the liner during firing, it would be necessary to impart to the tube an appreciable strength. The unbalanced relation resulting from a proposition of this character would increase the weight of the gun and nullify the attendant advantages of the composite barrel and the removable liner. 50 The relation between wall thickness and play space must be such that the liner will preserve the play space and not be permanently deformed when the play space is 55 at its maximum value due to the tolerances employed.

A further advantage resulting from the increase in the thickness of the liner and conducive to interchangeability is the fact that the muzzle portion of the liner can be made self-sustaining and need not be keyed to the tube to prevent its rotation. The omission of the keys at the muzzle is permitted because of the favorable position of other keys 60 in front of the powder chamber and in line with the projectile.

With the foregoing and other objects in view, the invention resides in the novel arrangement and combination of parts and in the details of construction hereinafter described and claimed, it being understood that changes in the precise embodiment of the invention herein disclosed may be made within the scope of what is claimed without departing from the spirit of the invention.

85 A practical embodiment of the invention is illustrated in the accompanying drawings, wherein:

90 Fig. 1 is a longitudinal sectional view of

the improved gun and removable liner, the play space being exaggerated;

Fig. 2 is a fragmentary, enlarged sectional view thereof at the breech and muzzle;

Figs. 3, 4 and 5 are transverse, sectional views on the respective lines of Fig. 1.

Referring to the drawings by numerals of reference:

The gun embodying the principles of the invention comprises a tube 5 within which is a liner 6 made of steel having a high elastic limit, this quality being incident to the particular composition of the steel or produced through methods of working or both. In order that the original inner dimensions of the tube may be preserved, irrespective of the extent of its use, the inner layer of the tube should also be overstrained by working to give it a permanent set or deformation to insure uniformity and the absence of defects.

Having determined the strength which the composite gun must possess, the corresponding total wall thickness is approximately equally divided between the liner and the tube as such a balanced relation will permit the employment of ample tolerances, favorably distribute the work which the liner and tube must jointly perform and enable the muzzle portion to be self-sustaining. The breech portion of the liner in which the powder chamber 7 is formed does not bear such a relation in regard to thickness and this variation is made as a manufacturing expedient to facilitate the cold working of a liner with a uniformly tapered exterior and a tube with a uniformly tapered interior.

With the wall thickness thus selected the tolerances on the external diameter of the liner and the internal diameter of the tube which may be safely employed may result in the provision of a play space which is more than three times the value of that allowance for play space which was introduced into the gun formula when determining the required strength for the thin liners of prior designs. For example, the value for play space is customarily .002 inch, whereas, in the gun embodying the principles of this invention, the value is .007 inch. Taking .003 inch as a minimum play space at the breech end, a plus tolerance and a minus tolerance of .002 inch may respectively be assigned to the internal diameter of the tube and the external diameter of the liner.

From a point directly forward of the location of the rotating band of a projectile, loaded in the gun, the value for play space increases gradually towards the muzzle where it may be .007 as a minimum with tolerances allowed as prescribed above.

The gradual increase in the value of the play space from breech to muzzle is inversely proportional to the powder pressure effective between these points. The additional play

space at the muzzle is permitted because the strength of the muzzle is such as to make it self-sustaining.

From the foregoing it is to be noted that the smaller value for play space pertains only to a relatively short distance at the breech which distance constitutes only about one-sixth of the total length of the liner. Accordingly, the insertion and removal of the liner from the tube may readily be accomplished.

The liner is formed externally with keys 8 in a position corresponding to that occupied by the base portion of a projectile 9 in the bore and these keys are receivable in key-ways 10 formed internally in the tube and disposed in a vertical plane so that the insertion of the liner will be facilitated. By virtue of the fact that the keys are in line with that portion of the projectile which on taking the rifling initially imparts torsional strains to the liner, it has been found that the keys usually placed at the muzzle may be omitted. This omission is a matter of great importance inasmuch as the incorporation of muzzle keys has been attended with considerable difficulty when provision is made for the independent longitudinal expansion and contraction of the liner.

We claim:

1. A gun comprising an outer tube, an inner tube, the outer diameter of said inner tube being less than the inner diameter of said outer tube to establish at all points therebetween a play space restorable after firing and the wall thickness of the tubes determined to permit manufacturing tolerances in diameters substantially doubling the minimum play space.

2. A gun comprising an outer tube, an inner tube, the outer diameter of said inner tube being less than the inner diameter of said outer tube to establish a play space restorable after firing, said play space having a gradually increasing value in the direction of the muzzle.

3. A gun comprising an outer tube, an inner tube of substantially the same wall thickness as the outer tube and the outer diameter of the inner tube being less than the inner diameter of the outer tube to establish at all points therebetween a play space restorable after firing.

4. A gun comprising an outer tube, an inner tube, the outer diameter of the inner tube being less than the inner diameter of the outer tube to establish at all points therebetween a play space restorable after firing and the muzzle portion of the inner tube being self-sustaining.

5. A gun comprising an outer tube, an inner tube, the outer diameter of the inner tube being less than the inner diameter of the outer tube to establish a play space restorable after firing and means preserving the play space located solely at the projectile occupy-

ing position of the liner for keying the liner to the tube, said keying means disposed in a vertical plane through the gun.

6. A gun comprising an outer tube, an inner tube, the outer diameter of the inner tube being less than the inner diameter of the outer tube to establish a play space restorable after firing and means preserving the play space located solely at the projectile occupying position of the liner for keying the liner to the tube.
